Atty's.

UNITED STATES PATENT OFFICE.

FREDERICK K. MAERZ, OF CLEVELAND, OHIO, ASSIGNOR TO THE SCOTT-ULLMAN COMPANY, OF CLEVELAND, OHIO, A CORPORATION OF OHIO.

DESIGN FOR AN ARM FOR ELECTRIC-LIGHT FIXTURES.

49,095.

Specification for Design.

Patented May 23, 1916.

Application filed March 24, 1916. Serial No. 86,511. Term of patent 3½ years.

To all whom it may concern:

Be it known that I, FREDERICK K. MAERZ, a citizen of the United States, residing at Cleveland, in the county of Cuyahoga and State of Ohio, have invented a new, original, and ornamental Design for Arms for Electric-Light Fixtures, of which the following is a specification, reference being had to the accompanying drawing, forming part hereof, wherein—

Figure 1 is a side elevation, and Fig. 2 a bottom plan view of the arm exhibiting my new design.

I claim:—

The ornamental design for an arm for electric light fixtures, as shown.

FREDERICK K. MAERZ.

Witnesses:

HUGH B. MCGILL,
BRENNAN B. WEST.
